UNITED STATES PATENT OFFICE.

HAROLD E. PORTER, OF BAYSIDE, NEW YORK.

MANDREL.

1,295,924.

Specification of Letters Patent.

Patented Mar. 4, 1919.

Application filed July 11, 1918. Serial No. 244,434.

To all whom it may concern:

Be it known that I, HAROLD E. PORTER, a citizen of the United States, residing at Bayside, New York, have invented certain new and useful Improvements in Mandrels, of which the following is a full, clear, and exact description.

This invention relates to mandrels or chucks, more specifically to expanding mandrels, *i. e.* mandrels adapted to be inserted into the opening or bore of the work and then expanded to grip the latter.

The aim of the invention is to effect certain improvements in the above mentioned devices with a view to facilitating the manufacture thereof, reducing the number of parts thereof and facilitating and rendering safe the manipulation thereof. As will hereinafter appear, the invention consists in various improvements which, though related in a generic sense, are capable of embodiment in different types of mandrels. In order to illustrate a reasonable number of different embodiments without undue multiplicity of views and repetition of illustrations I have omitted certain of the novel features in certain of the views. It should be borne in mind therefore that the novel features in each form may be embodied in other forms of mandrels, some of which are illustrated in the other figures.

Referring to the drawings which illustrate what I now consider the preferred forms of my invention:

Fig. 1 is a central section elevation of one form of mandrel.

Fig. 2 is a section on the line 2—2 of Fig. 1 but illustrating a modified form of actuating means.

Fig. 3 is a section on the line 3—3 of Fig. 1.

Fig. 4 is an elevation, partly in section of a modified form of mandrel.

Fig. 5 is a view similar to Fig. 1 but illustrating a further modification.

Fig. 6 is a section on the line 6—6 of Fig. 5.

Fig. 7 is a view similar to Fig. 6, omitting the attaching base and illustrating the parts in a different position.

Referring to Figs. 1, 2 and 3 it will be seen that I have shown a body portion 1 provided with an integral base or attaching member 2 for securing the mandrel to the face plate of a lathe or other machine. A plurality of cams 3 may be formed on said

body portion by milling the latter. To facilitate the formation of the cams a cylindrical portion 4, of the same radius as the distance from the axis of said body portion to the nearest element of the cam surface, may be provided to serve as a guide in the milling operation. The cylindrical portion 4, besides performing the above mentioned function, serves in conjunction with another cylindrical portion 5, adjacent a shoulder 6, to form a seat for a sleeve 7 rotatably mounted on said body portion. The sleeve 7 is provided with slots 8 in which a plurality of jaws or gripping members 9 are mounted in a position to be engaged by the cams 3. In order to prevent the said gripping members from dropping out I provide an integral lug 10 on each end of each of them. Recesses 11 are provided in said sleeve to receive said lugs 10. The above mentioned parts may be held in assembled position by an end plate or disk 12 secured to the body portion 1 by means of a bolt 13, in a position to engage the sleeve 7.

The mandrel, thus far described may be assembled as follows: The base 2 is secured to the face plate of a lathe or other machine. The gripping members are then inserted into the slots 8 of the sleeve 7, the latter is slipped over the body portion 1 into engagement with the shoulder 6 and the end plate 12 bolted in position. The gripping members 9 may now be projected to grip the work by causing relative rotation of the members 1 and 7 in one direction, thereby causing the cams 3 to thrust said gripping members 9 radially outward. By causing relative rotation of said members 1 and 7 in the opposite direction the jaws or gripping members are released.

The means for effecting relative rotation of members 1 and 7 may assume various forms. Thus in Fig. 2 the sleeve 7 is shown provided with a flange 14 which may be gripped and rotated by a spanner wrench or other tool, notches 15 being provided in said flange for this purpose. Preferably, however, I provide a hand-wheel 16, secured to said sleeve by a driving fit (see Fig. 1) to effect rotation of the latter. It should be noted that the hand-wheel 16 is dished somewhat and extends partially over the base 2 so as to protect the operator from the rotating, securing, or attaching, bolts of said base 2.

In Fig. 4 I have illustrated a different

type of expanding mandrel, *i. e.* one of the centering type. The parts 1, 2, 7, 9 and 16 correspond to the parts 1, 2, 7, 9 and 16 of Fig. 1 in both structure and operation and 5 need no further description. The body portion 1 has an integral extension 20 provided with a roller 21 at its free end to engage the work, thereby permitting the latter to rotate freely when the jaws or gripping members 9 are being projected or retracted. The roller 21 is rotatably but non-slidably held between a shoulder 22, on said extension 20, and a disk 23 having a threaded shank 24 which screws into the end of 10 said extension. The sleeve 7 in Fig. 4 is shown held against its shoulder 6 by means of a collar 25 detachably secured to the extension 20 by a set screw 26 adapted to seat in a depression in said extension.

20 It will be noted that instead of securing the hand-wheel 16' to the sleeve 7 by a driving fit, as shown in Fig. 1, I have shown the former keyed to said sleeve 7 at 28.

While all of the forms of the inventions 25 thus far described comprise means for projecting the jaws or gripping members and means for preventing the latter from dropping out of the mandrel, they lack means for positively retracting the jaws. In Figs. 30 5 to 7 I have illustrated one form of mandrel in which all of the above mentioned functions are accomplished.

As in the other forms, the mandrel illustrated in the last mentioned figures comprises a body portion 30 having an attaching base 31. A sleeve 32 is rotatably mounted on said body portion and held against axial movement by means of a shoulder 33, which it abuts at one end, and a plate 34 40 which engages the other end thereof. By providing the plate 34 with a central opening 35, to receive a boss 36 on the body portion 30, the latter may be provided with a centering hole 37 at its free end as well as 45 at its attaching end. The plate 34 is detachably secured to the body portion 30 by means of a plurality of bolts 38.

This form of mandrel comprises also a 50 plurality of jaws or gripping members 39 radially movable in slots in the sleeve 32 and constrained to occupy, at all times, a position between the body portion and said sleeve. As in the other forms, integral shoulders 40 are provided on said gripping 55 members in a position to engage the inner surface of said sleeve 32. As will be pointed out more specifically hereinafter these shoulders perform an additional and very important function.

60 The jaws or gripping members 39 together with the operating means therefor differ in structure from those illustrated in the preceding figures, being of the toggle type, and may be constructed as follows.

65 The body portion 30 is provided with a

plurality of sector shaped recesses 41 each terminating at its bottom or base in a cylindrical surface 42 having an axis 43 parallel to the axis of the body portion. Each of the jaws 39 is mounted in a corresponding 70 one of said recesses 41 and terminates, on the side adjacent the axis of the body portion, in a cylindrical surface of the same configuration as the surface 42. The members 39 therefore not only revolve about the 75 axis of the body portion 30, together with the latter, but are capable of oscillation with respect to said body portion about the axes 43, which may be termed the axes of oscillation.

80 The outer surfaces of the jaws 39 are cylindrical and coaxial with each other and with the body portion when said jaws are in the retracted position as illustrated in Fig. 7. The shoulders 40, above mentioned, are 85 also cylindrical but have their axes at 43 and are of such a radius that they engage the inner surface of the sleeve 32 tangentially at all times.

By virtue of the shoulders 40, and the co-operating structure, the jaws 39 are projected radially outward, beyond the surface of the sleeve 32 when the latter is rotated in a clockwise direction with respect to the body position. Furthermore the extent of projection depends on the angular distance of relative rotation of said body portion and sleeve, the limit of projection being illustrated in Fig. 6. In order to grip the work it is therefore only necessary to place the 100 latter on the mandrel and to rotate the sleeve 32. Although the remote or outermost edges of the jaws 39, and the corresponding axes 43 lie on the same radii of the body portion in the position illustrated 105 in Fig. 6 it will be noted that they are out of line in Fig. 7 so that a toggle action takes place in projecting the jaws.

When the jaws are in projected positions and it is desired to retract them the sleeve 110 32 should be rotated in a counter-clockwise direction with respect to the body portion 30. Due to the engagement of the shoulders 40 and the inner surface of the sleeve 32 said jaws will be positively moved to retracted position (see Fig. 7) on such rotation.

While a hand-wheel may be provided on the sleeve 32 for rotating the latter I have illustrated notches 51, in a flange 50 on said sleeve, into which a spanner wrench or other tool may be inserted to turn said sleeve. The front edges of the gripping members 9 are preferably beveled at 44 to facilitate assembling of certain kinds of work.

120 It is to be understood from the foregoing that I do not limit myself to the specific modifications and details of construction illustrated and described, as many departures may be made in points of detail and 125

other modifications resorted to without deviating from the true spirit and scope of my invention as set forth in the claims.

What I claim is:—

- 5 1. An expanding mandrel comprising a body portion, a plurality of cams on said body portion, gripping means carried by said body portion and operable by said cams and a cylindrical extension on said
- 10 body portion of a radius equal to the minimum radius of said body portion.
- 15 2. As an article of manufacture, a member having integrally formed peripheral cams, the longitudinal elements of which are parallel to the axis of said member, and a cylindrical extension of a radius equal to the distance from the axis of said member to the closest elements of said cams.
- 20 3. An expanding mandrel comprising a body portion having a plurality of cams thereon, gripping means, a cylindrical extension, on said body portion, of the same radius as the minimum radius of the latter and means comprising a sleeve rotatably mount-

ed on said extension and body portion for 25 causing said cams to project said gripping means.

4. A chuck comprising a body portion, a base on said body portion, gripping means supported by said body portion and means 30 comprising a hand-wheel, surrounding said base, for moving said means into gripping position.

5. An expanding mandrel comprising a body portion, a plurality of cams on said 35 body portion, gripping means carried by said body portion and operable by said cams, a cylindrical extension on said body portion of a radius equal to the minimum radius of said body portion, a securing flange on said 40 body portion, a sleeve rotatably mounted on said body portion and in which said gripping means are radially movable, and a hand wheel secured to said sleeve and surrounding said flange.

In testimony whereof I affix my signature.

HAROLD E. PORTER.
